UNITED STATES PATENT OFFICE

JAMES P. MARTIN, OF LANCASTER, PENNSYLVANIA, ASSIGNOR TO LANCASTER IRON WORKS, INC., OF LANCASTER, PENNSYLVANIA

AUTOMATIC BRICK MACHINE

Application filed March 5, 1927. Serial No. 173,028.

The invention forming the subject matter of this application relates to improvements in automatic brick machines of the type disclosed in United States Patents 1,341,798 and 5 1,454,165.

The main object of the invention is to simplify and improve the mechanism of machines of the aforesaid type by reducing the number of movable parts and increasing the efficiency 10 of the machine as a whole.

Another object of the invention is to provide machines of the type with improved means for regulating the pressure applied to the clay during the forcing thereof from the 15 pug mill through the dies and into the molds, and by which the pressure can be regulated without stopping the machine.

A further object of the invention is to simplify the push-out mechanism by eliminating 20 many of the commonly employed wearing parts and to provide this mechanism with novel safety shearing means to protect the machine and molds from injury in case of accident or overload.

Another object of the invention resides in 25 the arrangement of a vertical pug mill over the automatic mold feeding mechanism to effect reduction in power for operating the machine as a whole.

A still further object of the invention lies 30 in the arrangement of the press box outside the mill to render the parts accessible for replacement or repair and to lessen the tendency to form troublesome air pockets in the clay 35 inherent in machines where the plunger mechanism operates inside the mill.

Other objects of the invention will appear as the detailed description thereof proceeds.

In the drawings:—

Fig. 1 is a central vertical longitudinal section through the preferred form of the invention;

Fig. 1^a is a fragmentary sectional detail of an improved connection between the driving 45 crank and push-out mechanism of the invention;

Fig. 1^b is an end elevation of the parts shown in Fig. 1^a;

Fig. 2 is a plan on an enlarged scale of 50 the machine shown in Fig. 1, with the brick

dumping mechanism in front of the machine omitted;

Fig. 3 is an elevation, on the same scale as Fig. 2, of the rear end of the machine;

Fig. 3^a is a sectional detail of mechanism 55 for taking up slack in one of the sprocket wheels of this machine;

Fig. 3^b is a broken elevation of part of the framework supporting the mechanism shown in Fig. 3^a.

Fig. 4 is an elevation, on the same scale as Figs. 2 and 3, of the front of the machine, parts of the brick being cut away and shown in section;

Fig. 4^a is a fragmentary elevation of an 65 improved safety shearing connection for driving the sander shaft from the main drive;

Fig. 4^b is an elevation of the driving sprocket of the said shearing connection;

Fig. 4^c is an elevation of the parts of Fig. 70 4^a shown in a different position;

Fig. 4^d is an end elevation of the parts shown in Fig. 4^c;

Fig. 5 is a fragmentary sectional elevation 75 on an enlarged scale of the pressure adjusting mechanism of the machine shown in Fig. 1;

Fig. 6 is an elevation of a lost motion plunger plate of the adjusting mechanism;

Fig. 7 is a section on the line 7—7 of Fig. 6.

Fig. 8 is a plan of said plate;

Fig. 9 is a plan of the gear box of said ad-

justing mechanism;

Fig. 10 is a plan of the nut through which 80 said gear box is bolted to the pitman link of the press box; and,

Fig. 11 is a fragmentary longitudinal section through a modification of the machine.

As shown in Figs. 1 to 10 of the drawing, the main features of the present invention lie above the horizontal runners 1 and 2, extending rearwardly from the usual standards 3 and 4 which carry the usual mold return and sanding mechanism, suitable cross members and struts being used to connect the runners and standards to form a base on which the other elements of the invention are erected.

Transversely of the runners 1 and 2 there is suitably journaled the shaft 5 rotated by main drive shaft 61 through sprocket chain and gears to be described hereafter. Reduc-

tion gears 6 and 7 transmit rotation from drive shaft 5 to the crank shaft 8 which is also suitably journaled across the runners 1 and 2. A gear 9 secured to one end of crank shaft 8 meshes with a gear 10 keyed on to the hub 10' of a sprocket wheel 11 suitably secured rotatably on the stub shaft 12 which is shouldered at 12' to seat against the side of runner 2. The sprocket gear 11 is used to drive the sprocket gear 13 through the endless sprocket chain 14 meshing with both gears.

The stub shaft 12 is adjustably mounted on runner 2 to take up slack in chain 14. This is effected by seating the turned down extension 12" of shaft 12 in an arcuate slot 2' having its center at the axis of crank shaft 8, and by clamping the shaft in adjusted position in said slot by means of a nut 12''' engaging the screw threaded end of extension 12". Obviously, since the slot 2' is an arc having its center at the center of the crank shaft and gear 9, an adjustment of shaft 12 will not throw the gears 9 and 10 out of mesh with each other.

The sprocket wheel 13 is mounted to rotate freely on the shaft 15 (see Figs. 1 and 4) and is fixedly secured or cast integral with a boss 16 on which is formed the radial drive member 17. Keyed on to shaft 15 by the usual key and slot connection 18 is a radial arm 19 which is secured to said shaft 15 against axial movement thereon by means of a set bolt 20 and lock nut 21. The arm 19 has an extension 22 projecting laterally therefrom, and to this extension 22 there is secured by bolts 23 and 24 a pair of hardened steel plates 25 and 26.

These plates 25 and 26 extend beyond the end of extension 22 and have pivoted thereto, in the space between them, the hardened steel shear plate 27 by means of the pivot bolt 28. Each of the plates 25 and 26 is provided with opposed holes 29 and the shear plate 27 is provided with a hole 30 at the same distance from its pivot axis as the holes 29. The shear plate 27 is adapted to be swung about its pivot 28 and between said plates 25 and 26 until the hole 30 alines with holes 29 with the inner edge of rod 27 in the path of rotation of arm 17. A shear pin 31 of comparatively soft metal is inserted in the alined holes 29 and 30 and serves to transmit the rotation of arm 17 to arm 19 and hence to the shaft 15.

This shearing construction serves to disconnect shaft 15 from the driving mechanism in case the molds become jammed in the sander or receiving mechanism, the pin 31 being sufficiently hard to hold the plate 27 in driven connection with the driving arm 17 under normal working conditions only, and to be sheared by plates 25, 26, and 27 as soon as the molds become jammed in the sander or receiver or some accident occurs which would put the machine out of operation if some such safeguard were not provided.

In the prior art it has been customary to

provide for jamming of the molds by using two similar radial arms, one fixed to the shaft and the other to the driving sprocket, having matching apertures extending through each arm parallel to the shaft and adapted to receive the shear pin. In this old form of safety device, when the shear pin broke, and the machine was stopped to remove the obstruction and start up again, it was always necessary to bring the driving arm and driven arm into exact positions in which their shear holes were alined. This nearly always necessitates someone's getting down into the sand pit and working the shaft by hand until the shear arms match exactly, which is evidently a time consuming and costly operation. The present invention avoids this loss of time, since all that is usually necessary to connect the shaft for driving to the driving sprocket is to swing the shear plate 27 around its pivot until the hole 30 alines with hole 29 in which position the plate 27 is obviously in the path of rotation of the driving arm 19 and will make contact therewith when the machine is started up.

Returning now to the mold push out part of the machine, (see Figs. 1, 2 and 3) we have the crank throws 31' and 32 extending radially from crank shaft 8 and having a crank pin 33 connected thereto between their outer ends. The connecting rod 34 has one end thereof screwthreaded into a bifurcated bracket 35, which in turn is pivoted to a shaft 36 at one end of the mold push out 37, and a lock nut 38 locks the rod 34 in adjusted position in the bracket 35.

The other end of the rod 34 is slidably mounted in a sleeve 39 having a lateral extension 40 provided with a semicircular recess 41 to receive the crank pin 33. A plate 42 curved to fit the crank pin 33 is bolted to the extension 40 and cooperates therewith to secure this extension pivotally to said pin 33. The connecting rod 34 is provided with an aperture 43 adapted to be alined with apertures 44 and 45 in sleeve 39 and these apertures are each provided with steel bushings 46, 47 and 48, respectively, to receive a shear pin 49 to operate the rod 34 and push out plate 37 only until some obstruction jams the molds and causes the shear pin 49 to be severed by the steel bushings.

It will be obvious that the mechanism just described provides a very simple arrangement by which the throw of the push out plate can be adjusted, and which serves at the same time as an additional automatic safety shearing device to prevent injury to the molds or mechanism.

The next simplification and improvement of the old type of machine occurs at the front end of the machine where the bricks are dumped from the molds and the latter are dropped by gravity rearwardly to the sanding mechanism. In this case the mold stop

members 50 are not swung up to meet the filled molds during the inversion thereof, but are fixedly secured to the bracket 51, with the arms 52 carrying the rollers 53 inclined rearwardly to the horizontal sufficiently to let the emptied molds slide by gravity on to the chute 54. Only one of these members is shown in the drawing, but persons skilled in the art will readily understand that two 10 of said members positioned on opposite sides of the machine at the front end thereof are necessary to effect separation of the molds from the bricks.

Another radical improvement over the old 15 type brick machine resides in the vertical arrangement of the pug mill over the mold operating mechanism and the arrangement of the plunger mechanism on the outside of the mill. The pug mill casing 55 suitably 20 supported and braced vertically on the framework of the machine, has brackets 56 and 57 secured at opposite sides of the top thereof, and in these brackets there is journaled a shaft 58 having a spur gear 59 fixed to one end thereof and meshing with a pinion 60 on one end of a counter shaft 61 journaled 25 in bearing brackets 62 and 63 extending rearwardly of brackets 56 and 57.

A sprocket wheel 64 fixed to the other 30 end of drive shaft 61 is driven by an endless sprocket chain 65, which is in turn driven by a sprocket wheel 66' fixed to one end of the driving shaft 5.

The gearing just described serves as reducing gear to transmit rotation from the drive shaft 61, to the vertical shaft 66' carrying the horizontal pug knives 67, by means of the bevel pinion 68 fixed to shaft 58 and meshing with the large horizontal bevel gear 69 fixed to the shaft 66, which is journaled in suitable bearings in the casing 55. A wiper 70 fixed to the shaft at its lower end forces material through the discharge opening 71 into the path of the press platen 72 which reciprocates vertically on the outside of casing 55.

In order to reciprocate the press platen, the shaft 58 has a pinion 73 fixed to the end opposite the end carrying gear 59, and this gear 73 meshes with a gear 74 fixed on the end of a crank shaft 75 journaled in bearings 76 and 77 on the front of casing 55. The crank pin 78, extending between the throws 79 and 80 has one end of the pitman 81 pivoted thereto and the other end of this pitman 81 is pivoted to the pin 82 secured by set bolts 83 in arms 84 and 85 at the upper end of a slide link 86.

The platen 72 slides in a rectangular casing 87 formed by front plates 88 and 89 detachably secured as by bolts 90 and 91 to side extensions of the casing 55. The platen 72 is provided on its lower side with the usual air release valves 90', and is connected to the 65 link 86 so that its throw below the cut off

edge 91' of the discharge aperture 71 may be varied in order to regulate the pressure exerted upon the clay being forced through the die 92. A wear plate 93 suitably bolted to the back of platen 72 is adapted to slide over wear plate 94 fixed in any suitable manner to the front of the casing 55; and a wear plate 95 on the front of the platen 72 slides over similar plates 96 and 97 fixed to the inside of plates 88 and 89.

The pressure adjustment of the platen 72 is secured by a lost motion connection between the platen and link 86, the details of which connection are shown on an enlarged scale in Figs. 5 to 11 inclusive. These details include a plunger 98 provided at its lower end with lateral extensions 99 and 100 having suitable slots 101 adapted to receive the shanks of bolts (not shown) for adjustably securing the plunger to the platen.

The plunger 98 has sides 102 and 103 extending from the back 104 to the front of which a wear plate 105 is suitably secured and against which the link 86 and elements secured thereto are adapted to slide. The 90 opposed faces of the sides 102 and 103 are provided with slots 106 into which a plate 107 is adapted to fit and be inserted to provide for stepped adjustment of the throw of the platen.

The link 86 is mounted to slide against the wear plate 105 and between the sides 102 and 103 and is slidably secured to said plunger 98 by means of trunnions 108 and 109 extending laterally from link 86 into the slots 110 and 111, respectively, formed in said sides 102 and 103. As shown clearly in Fig. 5 the trunnions 108 and 109 are fixed to the link 86 by cotter keys 112 wedged into cooperating slots formed in each trunnion and the 105 bores 113 in which reduced ends 114 of said trunnions are seated.

Bolted to the bottom end of link 86 is a gear box formed by a nut 115 and a casing 116 in which is a bevel gear 117 bored centrally to permit a screwthreaded rod 118 to slide therethrough and to be rotated as it slides by the engagement of a key 119 fixed to said gear with a slot 120 extending lengthwise of said screw, which is screwthreadedly 110 connected with the nut 115 only.

A bevel pinion 121, fixed to shaft 122 extending through the bearing 123 of the gear box, serves to rotate the gear 117 in order to rotate and adjust the rod 118 in its nut 115. This shaft 122 may be rotated either by the hand wheel 124 secured directly to the end of shaft 122 as shown in Fig. 11; or it may be rotated by means of a hand wheel 125 fixed on one end of a shaft 126 suitably journaled on one side of the casing 55 and by an endless sprocket chain 127 engaging sprocket wheels 128 and 129 fixed to shafts 126 and 122, respectively as shown in Figure 4.

A closer plate 130 lined with a wear plate

131 is secured to the front edges of plunger 98, sides 102 and 103 by bolts 132. In order to guide the plunger 98 rectilinearly on the front of casing 55 the plunger is provided at its rear with dovetail slides 133, the rear faces of which are held in slidable contact with a plate 134 having upturned flanges 135 bolted to flanges 136 by bolts 137. To hold the plunger properly against plate 134 and to take up wear, a pair of plates 138 are mounted on the plate 134 to slide toward and from the plunger 98 and have their opposite inner edges beveled to engage the inclined sides of slides 133. Bolts 139 passing through slots 140 in plates 138 adjust the plates 138 relative to plate 134 to obtain the desired sliding contact with slides 133 and lateral adjustment is effected by means of the screws 141 threaded through lugs 142 projecting from plate 134 and engaging lugs 143 projecting from the face of each plate 138, lock nuts 144 being used on said screws 141 to lock them in their desired positions of adjustment.

The lower end of screw 118 has a bumper plate 145 fixed thereto to engage the plate 107 in the downward motion of the link 86, and obviously is the only means for imparting downward motion to the plunger and the platen fixed thereto.

As shown in Figure 11, the screw 118 is in its limit of downward adjustment so that there is no lost motion between the plunger 98 and link 86 and gearing carried thereby. This means that the platen is in its position of greatest compression and will reciprocate solidly with the link 86 and with the trunnions 108 and 109 in constant engagement with the tops of the slots 110 and 111.

The lift of the platen by the trunnions 108 and 109 is always the same; but its throw or downward displacement will evidently depend upon the distance through which the foot 145 may be adjusted from the plate 107 when the plunger is in its lowest position shown in Fig. 11. For example, if the foot 145 be raised, say, two inches above the plate 107 while the platen 72 is in its lowest position as shown in Fig. 11, the downward stroke of the platen thereafter will be two inches less, with the consequent and corresponding diminution in pressure exerted by the platen on the mud being forced through the die 92 into the molds. Obviously, when the plunger is pulled up by the trunnions 108 and 109, the mud forced under the platen by the pug mill wiper will hold the platen raised in its highest position until the foot 145 strikes the plate 107, and in the example just given, this cannot occur until the trunnions 108 and 109, link 86 and screw 118 have slid two inches downwardly in the plunger without moving either the plunger or the platen fixed thereto.

The modification shown in Fig. 11 is identical, so far as the plunger adjustment features are concerned, with that shown in Fig.

1. In Fig. 11, however, the pug mill is of the horizontal type. The details of this pug mill constitute no part of the present invention and are illustrated in part merely to show the adaptation thereof to my outside press mechanism in which my invention mainly resides.

The vertical form of pug mill is preferred for use with the outside press and automatic mold operating mechanism, because the gravity feed of clay to the press obviously consumes less power in its operation than the horizontal type.

This vertical form is preferred also because its use improves the quality of the product of the machine by reducing lamination and air pockets in the mixture immediately before its molding into bricks.

I claim:

1. In a brick machine, a casing having a die at one end, a press platen reciprocable in said casing toward and from said die, means for forcing plastic material into said casing between said die and platen, means for reciprocating said platen including a link having a lost-motion connection with said platen and having parts adjustable to vary the pressure of said platen on material forced thereby through said die.

2. In a brick machine, a casing open at one end and having an aperture through one side, a platen reciprocable in said casing toward and from said end; a support for a mold below said end; means for forcing plastic material through said aperture into said casing and in the path of said platen; mechanism for reciprocating said platen and including a plunger fixed to said platen, a link slidable in said plunger, and means for varying the distance of slide between said link and plunger.

3. In a brick machine, a pug mill having a pug shaft rotatable about a vertical axis therein and having a discharge aperture at the lower end thereof, a casing on the outside of said mill opposite said aperture, a press platen reciprocable in said casing a plunger secured to said platen, a link slidable on said mill and having an adjustable lost-motion connection with said plunger and gearing carried by said link to vary the length of lost motion slide between said link and plunger.

4. In a brick machine, a casing, a platen slidably mounted on said casing, means connected to said platen to reciprocate it on said casing, said means including a plunger having a foot fixed to said platen, a back having dovetail wings extending from each side thereof, parallel walls extending perpendicularly from one face thereof, and having slots therethrough, a link slidable between said walls and having pins projecting laterally therefrom into said slots, a contact plate seated between said walls, a screw threaded

into said link and having a head adapted to seat on said plate, and means for adjusting said screw to vary the distance between the head thereof and said contact plate when 5 plunger is supported by engagement of said pins with the upper ends of said slots.

5. A brick machine including a pug mill, a press platen mounted to reciprocate vertically on the outside of said mill, a hand wheel 10 on the side of said mill, and means connecting said wheel to said platen to vary the pressure thereof on material extruded from said mill into the path of said platen.

6. A brick machine including a pug mill, 15 a platen reciprocable on the outside thereof, means to reciprocate said platen and including parts having a relative sliding lost-motion movement, adjustable means to limit the distance of slide between said parts, and 20 a hand wheel supported on said mill for operating said adjustable means.

7. A brick machine including a pug mill, a platen reciprocable on the outside thereof, means to reciprocate said platen including 25 parts having a relative sliding lost-motion movement, a screw adjusting connection to one of said parts to limit the lost motion slide of the other part relative thereto, gearing for rotating said screw.

8. A brick machine including a pug mill, 30 a platen reciprocable on the outside thereof, means to reciprocate said platen including parts having a relative sliding lost-motion movement, a screw adjustably connected to 35 one of said parts to limit the lost-motion slide of the other part relative thereto, a gear slidably and non-rotatably connected to said screw, and means for rotating said gear.

In testimony whereof I affix my signature.
40 JAMES P. MARTIN.
